DRAFTSMAN'S TOOL HOLDER FOR A DRAFTING MACHINE

Mark T. Donahue, San Jose, Calif., assignor to Lockheed Missiles & Space Company, Inc., Sunnyvale, Calif.

Filed Oct. 29, 1974, Ser. No. 518,761

Term of patent 14 years

Int. Cl. D6—03; D8—08

U.S. Cl. D8—71

FIG. 1

FIG. 2

FIG. 4

FIG. 3

FIG. 1 is a perspective view of a draftsman's tool holder for a drafting machine showing my new design; and

FIG. 2 is a side elevational view;

FIG. 3 is a front elevational view; and

FIG. 4 is a top elevational view thereof.

I claim:

The ornamental design for a draftsman's tool holder for a drafting machine, as shown.
